UNITED STATES PATENT OFFICE.

THEODORE M. REIMERS, OF OAK PARK, ILLINOIS, ASSIGNOR TO SMITH, BARNES & STROHBER COMPANY, OF CHICAGO, ILLINOIS, A CORPORATION OF ILLINOIS.

TRACKER-BAR MECHANISM.

Application filed October 16, 1922. Serial No. 594,702.

To all whom it may concern:

Be it known that I, THEODORE M. REIMERS, a subject of the King of Denmark, and a resident of Oak Park, in the county of 5 Cook and State of Illinois, have invented certain new and useful Improvements in Tracker-Bar Mechanism; and I do hereby declare that the following is a full, clear, and exact description thereof, reference being had to the accompanying drawings, and to the letters of reference marked thereon, which form a part of this specification.

This invention relates to improvements in tracker bar mechanism for musical instruments and consists of the matters herein-after described and more particularly pointed out in the appended claims.

The primary object of the invention is to provide a simple and efficient mechanism 20 for maintaining full registry between the perforations of the music sheet and the openings in the tracker bar.

A further object of the invention is to furnish a mechanism of the kind, which is 25 of simple and economical construction, with comparatively few parts, capable of production at small cost, and which is so arranged and correlated with the music sheet mechanism that it may be readily installed in old 30 player pianos, or may be embodied in new pianos without material changes in the construction of said pianos.

A still further object of the invention is to provide a mechanism which is extremely 35 sensitive and quick in its operation so that positive registry is maintained at all times.

The aforesaid objects and advantages of the invention will more fully appear as I proceed with my specification.

40 In the drawings:—

Fig. 1 is a view in front elevation of a tracker box mechanism of a player piano, embodying my invention.

Fig. 2 is a view in elevation of the left 45 hand end of the tracker box.

Fig. 3 is a vertical section through the same on the line 3—3 of Fig. 1.

Fig. 4 is a vertical detail sectional view 50 on an enlarged scale, taken on the line 4—4 of Fig. 1.

Fig. 5 is a horizontal detail sectional view taken on the line 5—5 of Fig. 4.

Fig. 6 is an enlarged view of several of the parts shown at the right hand end of

Fig. 1, with some of said parts in a changed 55 relation.

Figs. 7 and 8 are vertical detail sectional views taken on the lines 7—7 and 8—8 respectively of Fig. 6.

Fig. 9 is a vertical detail sectional view on 60 a further enlarged scale, as taken on the line 9—9 of Fig. 8.

Fig. 10 is a perspective view of one of the bracket plates in which the ends of the tracker bar are supported. 65

Fig. 11 is a detail perspective view of one end of the tracker bar.

Fig. 12 is a longitudinal vertical section through the right hand end of the tracker bar, and shows the transposing mechanism 70 associated therewith.

Referring now in detail to that embodiment of the invention illustrated in the accompanying drawings as applied to the familiar player piano:—10 indicates the 75 open front tracker box or casing of the player piano. Said box includes the spaced upright side walls 11 and 12 respectively, a top wall 13 and a bottom wall or board 14 which is extended beyond the side wall 80 12 for the support of the operating gearing and motor.

15 indicates the perforated music sheet wound on a spool 15^a, which is removably connected to horizontal shaft parts 16 and 85 17, journalled in suitable bearings provided therefor in and near the top ends of the side walls 11 and 12 of the tracker box. The shaft part 17 extends beyond the side wall 12 where it has bearing in an upright 90 standard 18, which is one support for the unwinding and rewinding gear train. 19 indicates the spool upon which the perforated music sheet is wound in the playing operation. Said roll is mounted on horizontal shaft parts 20 and 21 respectively, journalled in suitable bearings in and near the bottom ends of the side walls 11 and 12 of the tracker box in the usual manner. The shaft part 21, like the shaft part 17, extends beyond the side wall 12, where it has bearing in the standard 18.

22 indicates the tracker bar. This tracker bar is a channel bar with a convexly rounded front wall 23 and top and bottom horizontal flanges 24, 25. The front wall has the usual row of openings 26 with which are connected the nipples 27, (see Fig. 3) one

nipple for each opening 26. To said nipples are connected the flexible tubes 28 which in turn are connected to the rigid tubes 23^a secured to the back wall of the casing 10. 5 The ends of the tracker bar 22 are supported in bracket plates 29, (see Figs. 1 and 10) secured to the front edges of the upright end walls 11 and 12 of the box,—the said end walls being cut away or notched in line with 10 the tracker bar so that the front wall of the tracker bar is flush with the front edges of said upright end walls. Each bracket plate has a front flange 30 which is screwed to the front edge of the associated side wall 15 and a side flange 31 which engages with the inner surface of said side wall. In each side flange is provided a centrally disposed opening 32 in which the ends of the tracker bar have bearing. In each end of the top 20 flange 24 of the tracker bar is a rectangular opening 24^a, (see Fig. 11) the flange being indented on each side of said opening to provide transverse grooves 24^b, the purpose of which will appear later. 25 34 indicates a horizontal rod located closely above the tracker bar 22. This rod is capable of both a limited endwise and rotative movement and carries opposed guide plates 35, which engage the edges of the music sheet 15. Said rod extends through holes 33 in the flanges 31 of the bracket plates 29, (see Fig. 10) and has a bearing support upon rollers 24^c arranged in the openings 24^a in the tracker bar. Each roller 30 has trunnions which bear in the grooves 24^b associated with said openings. A third roller 24^d (see Fig. 1) mounted on a pin 24^e fixed in the side wall 12 of the tracker bar, assists the other rollers to provide the antifriction bearing for said rod, so that frictional resistance is reduced to a minimum. 35 Each guide 35, as shown, is in the form of an elongated plate, with a sleeve 36 at its bottom end engaged upon the rod 34. 40 The guide plate 35 near the end wall 12 of the box is capable of a limited endwise movement with respect to said rod. A part of the metal forming the sleeve of the last mentioned guide plates 35, is cut and bent back 45 between its ends to form two stop lips 36^a, 36^b, (see Fig. 5). A radial stud 37 is fixed to the rod 34 in the opening left in the sleeve by said lips, and pivoted on the top end of said stud is a bell crank lever 38, the horizontal arm 38^a of which is weighted while the vertical arm 38^b engages the lip 36^b. Each guide plate has a flange 39 formed to define a groove 40, (see Fig. 5) to receive the edge of the music sheet and to hold it from accidental displacement from the guide plate. As the sheet weaves or shifts laterally, a corresponding movement is imparted to the guide plates 35 and a resultant endwise movement to the rod 34. The right 50 hand end 34^a of said rod extends beyond the right hand wall 12 for a purpose which will appear later. Secured to the rod end 34^a, near the end wall 12 of the box 10, is a small collar 34^b which limits the endwise movement of said rod. The rod 34, as before 55 mentioned, is capable of a limited rotative movement. Associated with that end of said rod outside of the end wall 11 of the tracker box, is a means for rotating the rod to normally urge the guide plates 35, 35 outwardly against the music sheet 15 to hold the same substantially taut. Fixed to said end of the rod is a short arm 34^c (see Fig. 2) the free end of which engages in the forked end 34^d of a lever 34^e the opposite end of which carries a weight 34^f. Said lever is pivoted on a pin 34^g carried by a laterally extending stud 34^h on the flange 31 of the associated plate 29 in such a manner as to be capable of a swinging movement in both a horizontal and a vertical plane. Laterally extending pins 34ⁱ on said flange 31 limits the vertical swing of the arm 34^c and lever 34^e. Thus, no matter in what longitudinal position the rod 34 happens to be in, the arm and lever arrangement will always act to rotate said rod to urge the guide plates 35 outwardly against the music sheet to hold it taut. 60 The shafts 17 and 21 of the spools 19 and 15^a are driven in their respective directions in the usual way, as follows:— 41 indicates a pneumatic motor mounted on the end extension of the bottom wall or board 14. Said motor drives a crank shaft 42 which carries a sprocket wheel 43 at one end; (see Fig. 1) 44 indicates a horizontal drive shaft arranged intermediate the shaft parts 17 and 21. This shaft 44 has bearing between its ends in the standards 18, and at its ends are upright standards 45 and 46 respectively, the one (45) being fixed to the outer surface of the box wall 12 and the other (46) being a part of a yoke which is fixed at its ends to the standard 18, as shown in Fig. 1. Fixed to the outer end of the shaft 44 near the standard 46, is a sprocket 47 which is driven by a chain 47^a from the sprocket 43 on the crank shaft 42. Feathered on the inner end of the shaft 44 adjacent to the standard 45 is an elongated spur pinion 48 which meshes with a spur gear 49 on the winding spool shaft part 21. Loose on the shaft 44 near the bearing 18, is a sprocket wheel 50 which, through a chain 51, drives a sprocket 52 on the music roll shaft part 17. 65 53 indicates a combined clutch shifting and braking bar which is pivoted at a point intermediate its ends on a bracket 54 extending laterally from the side wall 12. Said lever carries a pin 55 which extends into a peripheral groove in one end of the pinion 48, and said pinion has a longitudinal pin 56 which, when the pinion is shifted endwise in one direction, extends into the path of a similar pin 57 on the sprocket 50 so as to be 70 75 80 85 90 95 100 105 110 115 120 125 130

driven thereby. The bottom end of the lever is connected in any convenient manner with the actuating member in the control board of the piano, while the top end of said lever 5 coacts with the brake shoe 17^a associated with a disc 17^b on the shaft part 17. When the lever 53 is in the position shown in Fig. 1, the pinion 48 will drive the gear 49 to wind the perforated sheet upon the spool 19 and when said lever is in its other position, the sprocket 50 is clutched or connected to the pinion 48 through the pins 56—57 to drive the shaft part 17 to rewind the perforated sheet upon the spool 15^a.

15 58 indicates a relatively short horizontal shaft, arranged in a plane below the winding spool shaft part 21. The right hand end 59 is screw-threaded and extends through a threaded hole in the standard 46, said thread being relatively fine. The left hand end of said shaft bears in an aperture in the standard or bar 18 and to said end is fixed a peripherally grooved collar 60, (see Fig. 6). A vertically disposed arm 61 is operatively engaged at one end with the grooved collar 60 while the other end of said arm is connected by a horizontal rod 62 to the tracker bar 22, as will later appear.

20 Fixed to the shaft 58, adjacent the standards 46 and 18, are comparatively large spur gears 64 and 65 respectively. The gear 64 meshes with a smaller spur gear 66 loose on the shaft 44 near the sprocket 47. An arm 67 so connects the two gears 64 and 66 that they will move together longitudinally. The bottom end of said arm engages the grooved hub 64^a of the gear 64 and the top end of said arm is forked, (see Fig. 8) and engages the grooved hub 66^a of the gear 66 so as to maintain said gears in the proper relation. The gear 65 meshes with a pinion 68 journaled in a stud 69 carried by a second arm 70, said pinion meshing with a second pinion 71, loose on the shaft 44. The arm 70 is connected to the gears 65 and 71 in the same manner as the arm 67 is connected to the gears 64 and 66 so that the gear 65 and pinions 68 and 71 will move together longitudinally. The gear 66 and the pinion 71 each carries an inwardly facing clutch pin 72.

25 73 indicates a peripherally grooved collar, which is rotative with but capable of a limited endwise movement on the shaft 44 between the vertical planes of the gear 66 and pinion 71, said collar carrying outwardly facing clutch pins 74, adapted to engage either of the clutch pins 72, before mentioned. By this construction, it is apparent that when the collar 73 is shifted endwise on the shaft 44 in either direction, one of its pins 74 will engage with one of the pins 72, and drive the associated gear or pinion 67 or 71. The collar 73 is provided between 30 its ends with a peripheral groove 75 to re-

ceive the forked end 76 of an arm 77 (see Figs. 6 and 9) the other end of the arm being fixed to the extreme right hand end 34^a of the rod 34, before mentioned.

The operation of the tracker mechanism is as follows:—When a roll is being played, the marginal edges of the sheet 15 pass over the guide plates 35 and over the tracker bar 22 on the way to the winding spool 19. Should the sheet shift or weave laterally toward the right so that the perforations in the music sheet move out of register with the openings 26 in the tracker bar 22, an endwise movement in the same direction is imparted to the shift rod 34 and clutch collar 73, through the guide plate 35. This will move the collar toward the gear 66 and operatively connect the two together through the clutch pins 72 and 74 so that the gear will rotate with the clutch collar. As said gear is permanently in mesh with the gear 64 on the shaft 58, said gear 64 and shaft will be rotated in a reverse direction. By reason of the screw threaded bearing which the shaft end 59 has in the standard 46, the shaft 58 will move endwise toward the standard 46 and will, through the collar 60, and arm and rod 61, 62, shift or pull the tracker bar 22 to the right to bring the openings in the same again into register with the perforations in the music sheet. As said shaft 58 moves endwise toward the right under the screw thread action before mentioned, the gear 66 will move away from and out of engagement with collar 73, the parts all remaining in this last position as long as the perforations in the note sheet and the openings in the tracker bar 22 register.

35 Should the perforated music sheet now shift or move laterally toward the left, the collar 73 is caused to move endwise toward the left by means of the shift rod 34, until it is operatively connected to the pinion 71 through the pins 72 and 74. Said pinion, through the pinion 68 and gear 65, will rotate the shaft 58 in a direction the reverse of that just described, and will cause said shaft to move endwise toward the left, a like movement being imparted to the tracker bar through the connections before described, to bring the openings in the tracker bar again into register with the perforations in the music sheet. By reason of the endwise movement of the shaft 58 toward the left, the arm 70 moves in the same direction disengaging the pinion from the collar 73. Thus, no matter in what direction the music shifts or weaves, the tracker bar is shifted endwise to follow the weave of the music sheet, so that complete registry is maintained at all times.

40 In Fig. 12 is illustrated an adjustable connection between the tracker bar 22 and rod 62 by means of which the tracker bar may be shifted in either direction, with reference to

the music sheet, so that the music may be transposed to a higher or a lower key to accommodate the range of a vocal accompanist.

Attached to the bottom flange 25 of the tracker bar near its right hand end is a rectangular yoke 78, which includes upright end members 79 and 80 respectively. Said upright members have suitable openings, through which the free end of the rod 62 extends. In the top peripheral part of said end of said rod, is provided a plurality of notches 62^a which are spaced apart a distance corresponding to the spacing between the openings 26 in the web of the tracker bar. An arm 81 is pivoted at one end to the upright member 80 of the yoke and its other end is formed to provide a detent 82 adapted to engage in any one of the notches 62^a of the rod 62. The detent end of said arm carries a laterally extending pin 83 which projects forwardly through an arcuate slot 23^a (see Fig. 1) in the front web 23 of the tracker bar 22. Mounted on the other arm 79 of the yoke 78 is a leaf spring 84, which urges the arm 81 downwardly to yieldingly hold the detent 82 in one of the notches to connect the tracker bar 22 and rod 62 together. Should it be desired to transpose the music to a higher or a lower key, the pin 83 is moved upwardly of the slot 23^a to unlock the tracker bar from the rod 62, when the tracker bar may then be manually shifted to the left or right, a distance equal to that between one or more of the notches 62^a in the bar 62. When the proper adjustment has been made, the pin 83 is released and the detent 82 will enter the associated notch 62^a in the rod 62 and again lock the tracker bar and rod together. This will change the prior relation between the tracker bar openings and the note sheet openings to affect the transposition of music, a note or more according to the adjustment made between the tracker bar and rod 62.

As the gear and pinions on the shafts 58 and 44 are always in mesh, noise of shifting gears is eliminated.

The improved registry mechanism is extremely positive and quick in its action and is quite sensitive in operation so as to accommodate any minute weaving of the music sheet. The device is noiseless and does not include such small parts as will wear rapidly and thus develop a loose play which must be taken up by fine adjustments.

The stop 34^b and the arm 34^c on the shift rod 34 prevent accidental or careless displacement of the rod, by hand or otherwise, beyond the limits of the endwise movement which it is intended to have.

After a music sheet has been once played and it is rewound upon its roll, it has been found by actual operation that, upon a re-playing of the music sheet, no weaving occurs in the same. The bell crank 32 associated with the guide plate 35 engaging the

right hand edge of the music sheet, positively insures engagement of said guide plate with said edge, no matter how uneven said edge may be. Furthermore, the lever 34^c will always act to urge the guide plates toward the music sheet to keep the same taut, no matter what the longitudinal position of the shift rod 34 happens to be. As weights are used in each of the above instances, the operating force will remain constant, so that no fine adjustments need be made, as would be necessary if spring means were employed.

While in describing my invention I have referred to certain details of mechanical construction and arrangement of parts, I do not wish to be limited thereto except as may be pointed out in the appended claims.

I claim as my invention:

1. In a mechanism of the kind described, the combination of a music sheet roll shaft and an endwise movable tracker bar, a drive shaft for said roll shaft, a second shaft mounted for endwise movement when rotated, a device connecting said second shaft with the tracker bar, a rod, endwise movable in the weaving of the music sheet, permanently engaging means on said shafts for driving said second shaft in either direction, and means actuated in the endwise movement of said rod for connecting a part of said permanently engaged means to said drive shaft.

2. In a mechanism of the kind described, the combination of a music sheet roll shaft and an endwise movable tracker bar, a drive shaft for said roll shaft, a second shaft mounted for endwise movement when rotated, a device connecting said second shaft with the tracker bar, a rod, endwise movable in the weaving of the music sheet, two sets of gearing intermediate the drive shaft and said second shaft, said sets including gear elements loose on the drive shaft and gear elements fixed to said second shaft, and means actuated in the endwise movement of said rod for operatively connecting either of the loose gear elements to said drive shaft.

3. In a mechanism of the kind described, the combination of a music sheet roll shaft and an endwise movable tracker bar, a drive shaft for said roll shaft, a second shaft mounted for endwise movement when rotated, a device connecting said second shaft with the tracker bar, a rod, endwise movable in the weaving of the music sheet, two sets of gearing intermediate the drive shaft and said second shaft for driving said second shaft in either direction, said sets of gears including permanently meshing gear elements, the gear elements on the drive shaft being loose thereon, a clutch member keyed to the drive shaft between said loose gear elements, and means actuating said clutch from said rod for operatively con-

necting either loose gear element to the drive shaft.

4. In a mechanism of the kind described, the combination of a music sheet roll shaft and an endwise movable tracker bar, a drive shaft for said roll shaft, a second shaft mounted for endwise movement when rotated, a device connecting said second shaft with the tracker bar, a rod, endwise movable in the weaving of the music sheet, two sets of gearing intermediate the drive shaft and said second shaft for driving said second shaft in either direction, each set of gearing including a gear element loose on the drive shaft, means actuated by said rod for operatively connecting either loose gear element to said drive shaft, and means connecting the gear elements of each set to each other so that the gear elements of the active set will move longitudinally of the drive shaft when said second shaft is rotated by said active set of gear elements.

5. In a mechanism of the kind described, the combination of a music sheet roll shaft and an endwise movable tracker bar, a drive shaft for said roll shaft, a second shaft mounted for endwise movement when rotated, a device connecting said second shaft with the tracker bar, a rod, endwise movable in the weaving of the music sheet, two sets of gearing intermediate the drive shaft and said second shaft for driving said second shaft in either direction, each set of gearing including a gear element loose on the drive shaft, and an arm connecting the hubs of the gear elements of each set together, so that the gear elements of the active set will move longitudinally of the drive shaft, away from said means which connects the loose gear elements thereof to said drive shaft, when said second shaft is rotated by said active set of gear elements.

6. In a mechanism of the kind described, the combination of spaced, upright standards, a drive shaft journalled therein, a second shaft, one end of said second shaft being journalled in one of said standards and the other end of said shaft being threaded through the other standard, a large gear fixed to said second shaft near one standard, a second gear loose on the drive shaft and meshing with the large gear, an arm connecting said gears so that they will move together longitudinally, a third gear fixed to said second shaft near the other standard, a pinion loose on the drive shaft, a second pinion connecting the first pinion with said third gear, an arm connecting said third gear and pinions so that they will move together longitudinally, and a clutch collar on the drive shaft between said loose gear and loose pinion thereon, movable under the action of said rod to connect either said loose gear or said loose pinion to said drive shaft.

7. In a mechanism of the kind described, the combination of a tracker box having end walls, a tracker bar mounted in said end walls and over which a music sheet is drawn, shifting means connected to said tracker bar, a rod controlling the movement of said shifting means and capable of endwise movement under the weaving action of said music sheet, and means providing an antifriction bearing support for said rod.

8. In a mechanism of the kind described, the combination of a tracker box having end walls, a tracker bar mounted in said end walls, and over which a music sheet is drawn, shifting means connected to said tracker bar, a rod parallel with the tracker bar and movable endwise under the weaving action of the music sheet, said rod controlling the movement of said shifting means and members carried by the tracker bar providing an antifriction bearing support for said rod.

9. In a mechanism of the kind described, the combination of a tracker box having end walls, a tracker bar mounted in said end walls, and over which a music sheet is drawn, said tracker bar having recesses in its ends, shifting means connected to said tracker bar, a rod parallel with the tracker bar and movable under the weaving action of the music sheet, said rod controlling the movement of said shifting means and rollers mounted in the tracker bar recesses providing an anti-friction bearing support for said rod.

10. In a mechanism of the kind described, the combination of an endwise movable rod, guide plates on said rod, over which the margins of a music sheet must pass, one of said guide plates having a sleeve surrounding the rod and being capable of a limited endwise movement on said rod, a part of said sleeve being cut away to form an opening having a lip at one end thereof, a stud fixed to the rod and extending through said opening, and a lever mounted on said stud, one end of the lever being engaged with said lip and the other end being weighted, so as to normally urge said plate into engagement with the edge of the associated music sheet margin.

11. In a mechanism of the kind described, the combination of a music sheet roll element and a tracker bar element, the one being movable with respect to the other, means actuated in the weaving of the music sheet for imparting an endwise movement to one of said elements, a rod operatively connected to said last mentioned means, guide plates carried by said rod to engage the margins of the music sheet so that said rod is moved endwise under the weaving action of the music sheet, and weight controlled means operatively connected to said rod to rotate the same and urge the guide plates into engagement with the music sheet margins.

12. In combination, a tracker box, a tracker bar therein, capable of an endwise movement, and over which a music sheet is drawn, a rod mounted in the tracker box, 5 and capable of a limited rotative and endwise movement, guide plates on the rod for engaging the margins of the music sheet, and a weighted lever operatively connected to the rod for turning the same to cause the 10 guide plates to engage the music sheet margins, said lever and rod having engaging parts which will operate irrespective of the longitudinal position of said rod.

13. In a mechanism of the kind described, 15 the combination of a music sheet roll element and a tracker bar element, the one element being endwise movable with respect to the other, means controlled by the weaving of the music sheet for imparting a relative endwise movement between said elements to again bring them into registration, and devices connecting one of said elements with said last mentioned means, said devices being capable of being adjusted to change 20 the relation of the lines of music openings in the music sheet with the openings in the tracker bar for the purpose of transposition.

14. In a mechanism of the kind described, 25 the combination of a music sheet roll shaft and an endwise movable tracker bar, means controlled by the weaving of the music sheet 30

for imparting an endwise movement to the tracker bar, and a transposing device interposed between said last mentioned means and the tracker bar.

15. In a mechanism of the kind described, 35 the combination of a music sheet roll shaft and an endwise movable tracker bar, a normally stationary rod, and means connecting said tracker bar with the rod and capable of being adjusted to change the relation of the lines of music openings in the music sheet 40 with the openings of the tracker bar for the purpose of transposition.

16. In combination with an endwise movable tracker bar, a yoke within the tracker bar, a notched rod extending through said yoke, and a spring controlled detent mounted on the yoke and operable from without 45 the tracker bar for releasing the detent from the notch for purpose of changing the relative position between said tracker bar and rod.

In testimony that I claim the foregoing as 50 my invention, I affix my signature in the presence of two witnesses, this 14th day of October, 1922.

THEODORE M. REIMERS.
